CLARENCE M. THALIMER, OF MOUNT VERNON, NEW YORK.

HAT.

Application filed February 25, 1924. Serial No. 694,862.

To all whom it may concern:

Be it known that I, CLARENCE M. THALIMER, a citizen of the United States of America, residing at 10 Claremont Place, Mount 5 Vernon, New York, have invented a new and useful Hat, of which the following is a specification.

My invention relates to an improvement in hats and consists in providing a hat that 10 will have the appearance of a "derby," so called, with all of the advantages and comforts of a "soft" hat, so called.

In the accompanying drawings—

Fig. 1 is a plan view.

Fig. 2 is a front view in quarter section.

1 represents the hat crown which is of derby design, the stock used therein being of sufficient firmness and strength so that it will retain its shape substantially as blocked 20 without the use of stiffening material such as used in the regulation "derby" hat. 2 represents the brim portion. This likewise is of the customary "derby" design and is provided with the conventional curl at the 25 side edges. The entire brim may be reinforced with a suitable stiffening material, but the inner edge of the brim that contacts with the head is preferably left unsized so that it will readily conform to the contour 30 of the head, the same as the usual "soft" hat. In the drawings, the stippled portion of the brim, indicated at 3—3, designates conventionally that part of the brim it is preferred to stiffen. This not only permits the hat to 35 be easily lifted in salute after the manner of a derby but it also preserves the conventional roll at the edge of the brim and aids in helping the crown keep its shape.

There are many advantages that may be

attributed to this new construction, for example; the hat has every appearance of being the conventional "derby." In the event the crown should be knocked in or deformed it will not break as in the case of a derby but may be pressed back into shape. The 45 construction also has the advantage of being self-conformed to the head of the wearer, as in the case of a "soft" hat, thereby making it unnecessary to shape each hat to the head of the individual purchaser as in the case of 50 the conventional "derby."

The extent to which the brim is provided with stiffening material may be varied, as desired. While I am aware that so-called flexible derbies have been made, the common practice has been to provide stiffening material or sizing for the entire crown and brim, reducing the amount of stiffening material so that the hat is more conformable to the head than would be the case were more 60 stiffening material used. My invention contemplates providing stiffening material for only a part of the hat, preferably for only the outer part of the brim, relying upon the inherent stiffness or strength of the material itself to preserve the shape of the crown. Thus, not only does the hat conform to the head as easily as the ordinary "soft" hat, but it will permit almost all kinds of abuse 65 without injury.

I claim:

A derby hat comprising a soft flexible crown portion of sufficient firmness and strength to retain its shape substantially as blocked, and a stiff sized outer brim portion 75 for reinforcing and retaining the shape of the hat.

CLARENCE M. THALIMER.
